LAYING OUT TOOL FOR MAKING
METALLIC ELBOWS

Edward J. Gauthier, Flint, Mich.

Application October 14, 1942, Serial No. 462,011

7 Claims. (Cl. 33—158)

This invention relates to devices for laying out sheet metal work and more particularly to a tool for determining the outline or pattern of sheet metal elbows preparatory to cutting and fashioning the metal to form said elbows.

The object of the invention is to provide a comparatively simple and inexpensive tool of the class described by means of which the shape or configuration of the different pieces of sheet metal necessary to form a selected elbow or joint can be readily determined without using a separate plan or profile view of the parts as a guide to work from.

A further object of the invention is to provide an elbow laying out tool comprising a graduated rod or bar having spaced scribing sleeves slidably mounted thereon and adapted to register with said graduations for indicating the desired measurements of the pieces of metal to be cut.

A further object is to form one or more of the scribing sleeves with an interior collar or bushing and means for clamping the scribing sleeves in any selected position of rotative adjustment on said collar or bushing.

A still further object of the invention is generally to improve this class of devices so as to increase their utility, durability and efficiency.

In the accompanying drawings forming a part of this specification and in which similar numerals of reference indicate corresponding parts in all the figures of the drawings:

Figure 1 is a side elevation of an elbow laying out tool embodying the present invention.

Figure 2 is an end elevation.

Figure 3 is a vertical sectional view taken on the line 3—3 of Figure 1.

Figure 4 is a side elevation illustrating another form of the invention.

Figure 5 is a vertical sectional view taken on the line 5—5 of Figure 4.

Figure 6 is an enlarged view of a portion of the measurement bar or tube showing the graduations thereon.

Figure 7 is a vertical sectional view taken on the line 7—7 of Figure 5.

Figure 8 is a similar view taken on the line 8—8 of Figure 7.

Figure 9 is a vertical sectional view taken on the line 9—9 of Figure 7.

Figure 10 is a plan view of one of the rotating sleeves showing the parts thereof detached.

Figure 11 is an enlarged plan view showing the measurements or graduated marks on the bar or tube.

Figure 12 is a plan view showing a strip of

metal having the desired measurements thereon and before the same is cut to form an elbow.

Figure 13 is a side elevation of one of the segments constituting the elbow, and

Figure 14 is an end view thereof.

Referring to Figure 1 of the drawings, 5 indicates a solid bar or rod of any desired length and preferably angular in cross section, as shown. The angular faces of the rod 5 are provided with 10 a series of graduations or measurements 6 indicating the different lengths of metal strips forming the elbows which may be laid off with the tool, the number of pieces forming each elbow and the radii of said pieces. The bar is further 15 provided with graduations or measurements 7, by means of which the radius of each piece of metal for any desired length of elbow may be determined. The bar is also provided with an inclined row of designating marks 8 from which marks 20 measurements may be determined.

Slidably mounted for longitudinal movement on the rod or bar 5 are coating sleeves 9 and 10, the inner faces of which are angular in cross section, as indicated at 11, so as to prevent turning 25 movement of the sleeves on the bar while at the same time allowing said sleeves to be adjusted longitudinally thereof. The sleeves 9 and 10 are provided with lateral extensions 12 in which are threaded scribing points, indicated at 13. The upper portions of the scribing sleeves are provided with openings 14 in which are threaded clamping screws 15 for locking the sleeves in a selected position of adjustment on the bar 5, the head 16 of one of said screws having a supplemental screw 17 mounted for rotation therein and which acts as a finger-piece 30 when using the tool.

In Figures 4 to 10 inclusive of the drawings, there is illustrated a modified form of the invention, in which a hollow rod or tube 18 is employed 40 instead of the solid angular bar 5 shown in Figure 1. The hollow rod 18 is provided with surface graduations similar in character to the graduations shown in Figure 1 of the drawings and which graduations are indicated on an enlarged scale in Figures 6 and 11.

Slidably mounted on the rod or tube 18 are spaced scribing members 19 and 20 and fitting within said scribing members are interior collars 50 or bushings 21. The bushings 21 are free to slide on the rod 18 but are held against rotative movement with respect thereto by means of keys 22 fitting in keyways 23 formed in the rod 18, as best shown in Figure 8 of the drawings. Formed 55 in the bushings 21 are spaced V-shaped annular

grooves 24 and threaded in the scribing sleeves are retaining screws 25 having conical shaped terminals which fit within the grooves 24 and serve to prevent lateral movement of the scribing sleeves with respect to said bushings. Interposed between each bushing 21 and the rod 18 is a split resilient ring 26, the free ends of which bear against the key 22.

As a means for securing the scribing sleeves in different desired positions of rotative adjustment, each sleeve is provided with a clamping screw 27 which extends through a threaded opening in the adjacent sleeve for passage through any one of a series of radial openings 28 formed in the bushing 21 for engagement with the clamping ring 26. It will thus be seen that the bushings and scribing sleeves are slidable as a unit longitudinally of the hollow rod or tube 18. The bushings, however, are held against rotative movement on the rod 18 by means of the keys 22 while the sleeves are free to rotate on said bushings and are locked in adjusted position by means of the clamping screws 27. The sleeves 19 and 20 are provided with scribing points 29 similar to the scribing points 13 shown in Figure 1 of the drawings. The purpose of the resilient clamping springs 26 is to prevent the inner ends of the clamping screws 27 from coming in direct contact with the rod 18 and scratching or otherwise mutilating the measurement graduations thereon.

When it is desired to make an elbow of any desired size, as, for instance, an elbow having a six inch diameter and consisting of five pieces, each having a six inch radius, the clamping screws 27 are loosened and the scribing sleeve 19 rotated on the bushing 21 to the selected measurements on the tube 18 and then moved longitudinally of said tube to a position with the inner face of the scribing sleeve in vertical alignment with said measurements, after which the scribing sleeve 20 is adjusted on the tube until the inner face of the sleeve registers with the designating mark 8 opposite the selected measurements and the clamping screws on both sleeves tightened to prevent accidental movement of the sleeves. The tool is then positioned on a strip of metal 29 and by means of the scribing points 28 said metal strip divided into sixteen spaces, as indicated at 30 in Figure 12 of the drawings, said spaces indicating the length of the strip of metal from which the elbow is to be formed.

The scribing sleeve 19 is then moved into alignment with the designating character 8 opposite the measurements 6" 5 pc 6" R and the scribing sleeve 20 moved into vertical alignment with the group of graduations under the heading "5" in Figure 6 which graduations indicate the diameter of the elbow. After the scribing points are set in this manner, the clamping screws are tightened and the tool moved to a position at substantially right angles to its original position with one of the scribing points on the central line intersecting the transverse line designated 6" in Figure 12 and the other scribing point moved transversely of the strip of metal to the opposite longitudinal margins thereof to determine the circumference of the strip at a selected point or points. In other words, this transverse scribing of the metal strip first starts on the lines 6 and 4, shown in Figure 12 of the drawings, then 7 and 3, then 8 and 2 and so on throughout the range of the measurements indicated in Figure 6 of the drawings, thereby marking the sheet metal strip in the manner shown

in Figure 12. After the metal strip has been marked in this manner, it is severed transversely to form segments which are subsequently rolled into the desired shape and soldered or otherwise united thereby to form the elbow or joint.

The operation of the device shown in Figure 1 is similar to that shown in Figure 4 of the drawings, with the exception that it is not necessary to rotate the scribing sleeves 9 and 10 on the bar 5.

It will thus be seen that there is provided a comparatively simple and thoroughly efficient tool of the character described, by means of which elbows of different sizes and different numbers of pieces can be made quickly without employing the usual plan or profile sheet as a guide in cutting and fashioning the metal used in the construction of said elbows.

It will, of course, be understood that the devices may be made in different sizes and shapes and constructed of any suitable material without departing from the spirit of the invention.

Having thus described the invention, what is claimed as new is:

- 25 1. A tool of the class described comprising a rod having graduations thereon corresponding to the length of a strip of metal necessary to make a selected elbow, the number of elbow pieces in said strip and the radii of said pieces, spaced bushings locked against rotation on the rod but free to slide thereon, sleeves mounted for rotation on said bushings and provided with scribing points, and clamping members extending through the sleeves and bushings for holding said sleeves in adjusted position.
- 30 2. A tool of the class described comprising a rod having graduations thereon corresponding to the length of a strip of metal necessary to make a selected elbow, the number of elbow pieces in said strip and the radii of said pieces, coating bushings free to slide on said rod but locked against rotative movement, sleeves mounted for rotation on the bushings and provided with scribing points, split rings interposed between the bushings and the rod, and clamping screws threaded in the sleeves and extending through the bushings for engagement with said split rings for clamping the sleeves in adjusted position.
- 35 3. A tool of the class described comprising a tubular member having graduations thereon, spaced bushings slidably mounted on the tubular member but held against rotative movement thereon, said bushings being provided with a plurality of radiating openings, scribing sleeves mounted for rotation on the bushings, resilient rings interposed between the bushings and the tubular member, and clamping screws carried by the sleeves and adapted to pass through the adjacent openings in the bushings for engagement with the resilient rings to hold the sleeves in adjusted position.
- 40 4. A tool of the class described comprising a tubular member having graduations thereon, bushings slidably mounted on the tubular member but held against rotative movement thereon, said bushings being provided with oppositely disposed annular grooves and intermediate radiating openings, scribing sleeves slidably mounted on the bushings, retaining screws carried by the sleeves and fitting within the grooves, and clamping screws threaded in the sleeves and extending through the adjacent radiating openings for holding the sleeves in adjusted position on the tubular member.
- 45 5. A tool of the class described comprising a

hollow rod having graduations thereon and provided with a longitudinal key seat, bushings slidably mounted on the rod and provided with keys fitting within said seat, split rings interposed between the rod and said bushings, said bushings being provided with spaced substantially V-shaped annular grooves and intermediate radiating openings, sleeves mounted for rotation on the bushings and provided with scribing points, retaining screws threaded in the sleeves and provided with pointed terminals loosely fitting within the grooves, and clamping screws threaded in the sleeves and extending through the adjacent radiating openings for engagement with the rings for clamping the sleeves in adjusted position.

6. A tool of the class described comprising a rod having graduations thereon, coacting bushings slidably mounted on the rod but held against rotative movement, sleeves mounted for rotation on the bushings and provided with depending scribing members, means carried by the sleeves and coacting with the bushings for preventing lateral displacement of said sleeves, and clamping

devices carried by the sleeves and extending through openings in the bushings for clamping said sleeves in a selected position of adjustment on the rod.

- 5 7. A tool of the class described comprising a hollow rod having a longitudinal keyway formed therein, tubular bushings slidably mounted on the rod and provided with keys fitting within the keyway, split resilient rings interposed between the bushings and rod and having their ends bearing against the adjacent keys, said bushings being provided with spaced circumferential grooves and intermediate radiating openings, scribing sleeves mounted for rotation on the bushings, retaining screws carried by the sleeves and fitting within the grooves for preventing lateral displacement of the sleeves with respect to the bushings, and clamping screws threaded in the sleeves and extending through the adjacent radiating openings for contact with the split rings for clamping the parts in adjusted position on said rod.
